(57) **CLAIM**

The ornamental design for a vehicle light as shown and described.

DESCRIPTION

FIG. 1 is a left front perspective view of a vehicle light; FIG. 2 is a front elevation view thereof; FIG. 3 is an enlarged front elevation view thereof taken from FIG. 2; FIG. 4 is an enlarged front elevation view thereof taken from FIG. 2; FIG. 5 is a rear elevation view of the vehicle light; FIG. 6 is a top plan view thereof; FIG. 7 is a bottom plan view thereof; FIG. 8 is a left side elevation view thereof; FIG. 9 is a right side elevation view thereof; and, FIG. 10 is a front view of the vehicle light shown in use. The broken lines in FIGS. 2, 3, and 4 delineate areas of the figures shown enlarged and form no part of the claimed design.

The deemphasized portions in FIG. 10 show environmental structures and form no part of the claimed design.

1 Claim, 6 Drawing Sheets
